UNITED STATES PATENT OFFICE

BLAINE M. TUXHORN, OF KANSAS CITY, MISSOURI, ASSIGNOR TO AERO-SAFE MOTORS CORPORATION, OF KANSAS CITY, MISSOURI, A CORPORATION OF MISSOURI

AIRPLANE-LOADING DEVICE

Application filed August 25, 1927. Serial No. 215,378.

My invention relates to aircraft and more particularly to means for loading airplanes while in flight, the object being to enable an airplane to pick up a load without hazard 5 of damage to the airplane, load, carrier or loading means due to the stresses arising when a moving body engages a still body.

The principal problem involved in loading airplanes while in flight is connected with 10 overcoming the inertia of the load, a relatively small weight of load to be picked up offering a relatively large and hazardous resistance due to the speed of the plane. An incidental problem has been to provide loading 15 means avoiding danger of damage to the plane approaching the load and contacting it, and enabling the plane operator to direct the pickup means with sufficient accuracy to grasp the load.

20 In accomplishing the objects stated I have provided improved details of structure, the preferred forms of which are illustrated in the accompanying drawings, wherein:

Fig. 1 is a perspective view of the invention.

Fig. 2 is a detail perspective view of the upper end of a standard and engaged load loop.

Fig. 3 is a longitudinal sectional view of 30 a projecting device having a load associated therewith.

Fig. 4 is a detail view of the lower end of one of the standards partly broken away, a base member being shown in section.

35 Fig. 5 is a diagrammatic view of the wiring system for releasing the projector.

Fig. 6 is a section of the projecting device on the line 6—6, Fig. 3.

Referring in detail to the drawings:

40 1 designates generally a supporting element comprising the spaced standards or posts 2 and 3, the standards having the notches 4 at their upper ends to receive an elastic element 5, preferably a cord that is designed for

45 attachment to a container 6, for example by extending the cord through the bail 7 of the container and joining its ends to form a loop.

A track or guide 8 is provided to support 50 the container comprising preferably a tubular member or barrel pivotally supported by

brackets 9 on spaced blocks 10 disposed on a platform 11. The guide is provided with an adjusting leg 12 pivotally mounted in ears 13 on the forward portion of the barrel having openings 14 for engagement with a pin 55 15 disposed through openings 16 in supporting brackets 17 positioned on the platform 11 in advance of the spaced blocks 10. The pivotal support and pivoting leg provide for the elevation or depression of the forward 60 end of the guide and fixing it in a desired position.

The general structural features mentioned provide for the arrangement of the elastic cord, which is preferably an airplane shock 65 absorber cord, in the notches at the upper edges of the standards to produce a horizontal member 18 of the cord, the standards being for example twelve feet high and disposed twenty feet apart so that an airplane generally designated 19, having the axle 20 from which a hook member 21 provided with a hook 22 depends, may in flight engage the cord to pick up the load.

70 The fact that the cord is elastic and is easily released from the notched standards, measurably reduces the hazard of picking up a load which the container may hold or represent, by delaying the fully effective traction or drawing influence of the airplane on the load. The 80 load thus engaged may be elevated to be handled by the aviator, by means of the draw cable 23 attached to the hook member 21. Additional means for reducing the hazard and furthering the efficiency of a pickup include the elements for supporting the standards 2 and 3. Foundation or base blocks 24 and 25 of concrete or like substantial material are sunk suitably in the ground, and on these 85 base blocks the standards are movably supported. The standards have globular footing members 26, the lower segments of which are truncated to provide the flat seating portions 27 for vertical normal positioning of the standards.

90 Each globular footing member is provided with a nether opening 28 across which extends a pin 29 fixed in the member at right angles to the plane of the spaced standards; and over the pin 29 an elastic element 30 100

is arranged, which extends downwardly through a vertical opening 31 in the foundation or base block to an anchoring cross plate 32 that is fixed on the bottom of the block, 5 the elastic element being looped over said plate or otherwise engaged therewith. The standards tend, through the levering influence of the elastic elements recited, to retain a vertical position and to be returned to vertical 10 position if tilted or oscillated on the globular footings, and are permitted to oscillate.

I provide, further, means for discharging the container from the tubular guide at substantially the moment of engagement of the 15 container by the airplane, including a piston 33 slideable in the guide and having arms 34 projecting laterally through side slots 35 of the guide; and laterally extending bars 36 fixed on the forward portion of the guide in 20 alignment with the slots and projecting arms of the piston. Elastic cords 37 are fixed to the projecting piston arms and to the bars on each side of the guide, so that retraction of the piston rearwardly in the guide will 25 tension the cords. A rod 38 having an eye 39 extends rearwardly from the piston through a large opening 40 in the rear end wall 41 of the guide, whereby the piston may be retracted, for example, by attaching the rod 30 to the hook 42 on a rope 43 that may be wound on a windlass 44 against the tension of the cords 37.

The piston may be latched in retracted and tensioned position by the engagement of a 35 tooth 45 on the rod with a latching member 46 pivotally supported at 47 by a bracket 48, the release of the latch enabling the piston to project a container that may be positioned in the guide adjacent the piston.

40 The latch may be manually operated but I show one means of automatically actuating it synchronously or in timed relation with the withdrawal of the load-supporting loop by the airplane, including a magnet element 45 49 in the housing 48, the magnet being served by wires 50 and 51, the latch 46 constituting the armature of the magnet and being released from engagement with the piston bar upon energization of the magnet. The circuit of 50 the wires 50 and 51 is completed through terminals 52 and 53 having arcuate contact plates 54 and 55 positioned on the foundation blocks adjacent the globular footing members of the standards, and terminals 56 55 and 57 fixed in the said globular footing members and having contact points 58 and 59 adapted to contact the arcuate plates 54 and 55 upon tilting of the standards to a degree regulated by the spacing of the contact points 60 from the plates due to adjustment by set screws 60.

The circuit is suitably provided with current so that when the standards tilt to complete the circuit the magnet is energized and 65 the latch released to permit the piston to

respond to the tension of the elastic cord and project the container.

The guide 8 is preferably provided as adjustably movable, for example, by moving its supports through slots 61 and 62 of the platform, for shorter or longer delay of pull on the load through the loop. 70

In using the invention, the elements having been constructed and assembled as described, a load such as gasoline or oil for the use of the airplane, mail, or other message; or merchandise, is installed in the container or provided in suitable form. The elastic element 5 is then engaged with the container and its portions looped in the notches in the 75 upper ends of the standards. The piston rod is secured to the hook of the windlass and the piston retracted against the tension of the cords 37, and retained by the latch 46, the windlass hook being then released from the 80 rod. The container is positioned in the guide member in contact with the piston, such positioning not necessarily involving 85 tensioning of the elastic element 5.

The guide member is adjusted and positioned for the particular purpose and, for example, at a slight upward angle in the direction of the probable airplane flight, by the adjusting elements described. 90

When an airplane approaches, it is so guided that the depending hook engages the laterally extending elastic element 5 and the advance of the airplane causes the element to tilt the standards. A small extent of tilting results both in the release of the engaged 100 elastic element from the notches of the standards and in the contacting of the contact plates 54 and 55 by the members 58 and 59 of the tilted standards, completing the circuit for energizing the magnet whereby the 105 latch constituting the armature of the magnet is withdrawn from engagement with the piston rod. The piston rod being thus released, the piston is snapped forward in the guide member by the tensioning cords, projecting the container forwardly in and outwardly from the guide member, and in substantially the direction of flight of the airplane. 110

The load, namely, the container, having 115 a certain amount of inertia which tends to cause the elastic element 5 to be extended when engaged by the airplane member, is therefore projected by the released piston at substantially the initial moment of influence 120 of the drawing force of the airplane, whereby the inertia is overcome by the projector and the airplane is relieved of the duty. 125

Should a part of the airplane accidentally touch one of the posts, the latter will tilt and so move away to prevent damage to the airplane. The posts return to normal position upon withdrawal of any influence tilting them. 130

The particular proportions and relative

positions of parts of the structure may be adapted to the features of a particular loading point or station, the service required, or the probable usual speed of airplanes picking up loads therefrom. The horizontal 5 spacial relation of the guide or barrel to the vertical plane of the posts is a factor, for example in the regulating of the interval between the grasping of the container cord loop by the airplane and the pull by the cord on the container. The length, shape or position of the contact fingers 56 and 57 on the posts, affecting the distance they travel upon tilting of the posts to make contact with the 10 plates to complete the magnet-energizing circuit, is a factor regulating the delay between grasping of the container loop by the airplane and projection of the container.

A guide may be movable at right angles 20 to the plane of the posts, or the posts may be movable, to permit adjustment of the spacial relation between the guide and the posts.

When the guide is relatively distant from the posts and behind them with reference to 25 the direction of flight of an airplane using the station, the load cord will obviously be inclined upwardly from the container to the top of the posts and forwardly in the flight direction, the loop being installed forwardly 30 on the posts and being brought back rearwardly between the posts to be connected with the container. A traveling airplane will therefore hook the load while in an advanced position over the load, so that the cord is extended and tensioned, the posts are tilted, and 35 the projector released, upon relatively short travel of the airplane after hooking the load, a desirable arrangement at slow airplane speed. When the guide is positioned more 40 forwardly, the airplane catching the loop travels several feet before causing full extension of the cord; the posts are tilted at the instant of or before the passing of the airplane over the load; and the projector will 45 therefore be actuated to discharge the load at an earlier moment relative to the passage of the airplane traveling at a high rate of speed, whereby hazard of strain on the load cord is avoided.

50 Similar accommodation of the extent of delay in discharge of the load relative to the passing of the airplane, is provided for in the adjustment of the contact members of the posts. When the contact members are 55 positioned with their ends relatively close to the contact plates of the base, a small degree of tilting of the post will cause contact and closing of the circuit to energize the magnet and release the projector, a practice desirable 60 when a swiftly moving airplane is picking up a load, so that the load will be projected the more promptly. When the contact members are spaced to a greater degree from the contact plates, the posts must tilt to a greater 65 degree to cause release of the projector; and

so adjusted the structure is accommodated to a less swiftly moving airplane so that the load may not be projected in advance of the moving airplane.

While I have described my device as employing a piston actuated by elastic cords for projecting a container having a load, I suggest other means of accomplishing similar purposes which are intended to be included and implied in the claims hereto appended. 70 For example, the guide member may be provided with means for receiving an explosive, and means may be provided for timely detonating of the explosive, for discharging and projecting a load from the guide member in the direction of the airplane flight; the elastic loop described or analogous means being used for supporting the container. A spring may serve as the projector, means being provided whereby the tilting posts, or other factor operating synchronously with the passing of the airplane, may release a latch to render the spring effective. Pneumatic means may be employed in projecting the load. The explosive, pneumatic, metallic spring, elastic 80 cord, or other discharging means may be suitably controlled by the operation of the tiltable posts or otherwise, either electrically or mechanically, or pneumatically.

85 The device may be adapted for other carriers than airplanes, for example, carriers operating on land or water may pick up articles or loads by the means disclosed; and the supporting elements may be installed on the ground, on buildings, boats or airplanes for 90 the use of airplanes.

95 My experience has disclosed the value of the several features used either singly or in co-operation, namely, the elastic load-supporting cord releasably engaged on spaced 100 posts, the tiltable structure of the posts, for return to vertical position, the projecting device, and the control of the projecting device by the tiltable posts; which enable an airplane to pick up a load without hazard to 110 the airplane, load, or loading device.

105 What I claim and desire to secure by Letters Patent is:

1. A device of the character described comprising a movable supporting element, a 115 member releasably carried by the supporting element for attaching to a container, and means including elastic cords operable by movement of said supporting element for projecting the container.

120 2. A device of the character described for enabling an airplane to pick up a container, comprising a supporting element, an elastic member releasably carried by the supporting element to be attached to the container, a 125 guide element for seating the container, and means for projecting the container including a trigger operated by a movement of said supporting element.

3. In a device for enabling an airplane to 130

pick up a container, supporting posts, a container-elevating member releasably carried by the posts, a slotted tubular guide member adjustably positioned adjacent said posts 5 adapted to receive the container, a piston slideable in the tubular member, means for latching the piston in retracted position, means having a member movable in the slots of the tubular member for projecting the piston forwardly in the tubular member to discharge 10 the container therefrom, and means connected with the posts for causing the latch to be released to permit projection of the piston.

4. In a loading device for airplanes, supporting posts, a container-carrying member releasably carried by the posts, a tubular guide member adjustably positioned adjacent said supports and adapted to receive a container, a piston slideable in the tubular member, elastic means having portions fixed on the tubular member for projecting the piston forwardly in the tubular member to discharge 15 the container, and means connected with the posts for effecting the projection of the piston.

5. In a loading device for airplanes, a supporting element including a tiltable standard having means for automatic return to normal position, means for tilting the standard including an element to be connected with the load for releasable engagement with the supporting element, means for projecting the load, means operated by tilting of the standard for rendering the projecting means effective and means connected with the airplane 20 for engaging said load-connected element to tilt the standard and receive the load.

6. In a device for enabling an airplane in flight to pick up an article, an article-carrying element having a member releasably supported in the path of the airplane, means for projecting the article in the general direction of the airplane flight, means operated by movement of the said member for rendering said projecting means effective, and means automatically restoring said second named means to pre-operated position, the airplane having means to apprehend said member to be carried away thereby.

7. In a device for enabling an airplane in flight to pick up an article, an article-carrying element having a member releasably supported in the path of the airplane, means for projecting the article carrying element in the general direction of the airplane flight, and means actuatable upon movement of the said member for rendering said projecting means effective, comprising an electric circuit, a projector-releasing element actuated by the current of the closed circuit, and means operated by movement of said member for closing the circuit, the airplane having means to apprehend said member to be carried away thereby.

8. In a device of the character described, a tiltable standard, a container-supporting cord for engagement with the standard, a projector

adapted to receive the container, and electric means for rendering the projector effective including an electric circuit and a contact on said standard adapted to close the circuit upon tilting of the standard.

9. In a device of the character described, a tiltable standard, a container-supporting cord engageable with the standard, a projector adapted to receive the container, and electric means for rendering the projector effective including an electric circuit and means operable upon tilting of the standard for controlling the circuit.

10. In a device of the character described, a container-carrying member, a support, and a projecting element comprising a shell, means for horizontally adjusting the position of the shell with reference to the support, and means for rendering the projector effective operated by movement of the container-carrying member.

11. In a loading device for airplanes, a standard, means tiltably supporting the standard, a load carrier engageable with the standard and adapted to tilt the same and releasable therefrom upon tilting of the standard, means for discharging the load including a trigger operated by tilting of the standard, and means connected with the airplane for engaging said load carrier to tilt the standard.

12. In a loading device for airplanes, a support, a load carrier adapted to be movably positioned on the support and including a loop engageable by the airplane, and means including an elastic cord fixed to the support and operable against the load carrier for projecting the same.

13. In a device for transferring a load to an aircraft in flight, including a guide for movably supporting the load, means for projecting the load, and a load cord support, an elastic load cord adapted to be fixed to the load and having a portion for mounting on the cord support to form a loop for engagement by an aircraft, and means including a member mounted on said cord support and responsive to movement of the load cord upon engagement of the same by the aircraft for rendering said load-projecting means effective.

In testimony whereof I affix my signature.
BLAINE M. TUXHORN.
